UNITED STATES PATENT OFFICE.

HYMAN ABRAMOVITZ, OF NEW YORK, N. Y.

CHANGE-MAKING MACHINE.

1,166,302.

Specification of Letters Patent. Patented Dec. 28, 1915.

Application filed June 16, 1915. Serial No. 34,414.

To all whom it may concern:

Be it known that I, HYMAN ABRAMOVITZ, a citizen of the United States, and a resident of the city of New York, borough of Manhattan, in the county of New York and State of New York, have invented a new and Improved Change-Making Machine, of which the following is a full, clear, and exact description.

10 This invention relates to coin handling devices and has particular reference to means whereby a cashier may by simple and easily operated mechanism deliver to a purchaser or a customer the necessary change when a purchase is made and a sum of money in excess of the purchase price is tendered.

15

Among the objects of the invention, more definitely stated, is to provide a casing of a suitable size provided with reservoirs or chambers for coins of as many different denominations, each chamber having associated with it a plunger movable substantially at a right angle to the axis thereof whereby, upon manipulation of the plunger, a single coin will be delivered from such chamber and all of the coins from any of the chambers whose plungers are manipulated will fall or roll into a single pocket for convenience of delivery to the customer.

20 A further object of the invention is to provide means to indicate to the cashier the fact that any of the chambers are empty and thus prevent the possibility of delivering an inaccurate amount of change to a customer.

25 A still further object of the invention is to provide in a device of the nature above set forth means whereby each of the plungers is required to be forced to its full distance before it will return automatically to its normal position, and whereby the locking of the plunger mechanism from proper operation is prevented and whereby furthermore the several chambers or magazines are left free to be lifted bodily upwardly out of normal position for filling, emptying or other purposes.

30 With the foregoing and other objects in view, the invention consists in the arrangement and combination of parts hereinafter described and claimed, and while the invention is not restricted to the exact details of construction disclosed herein, still for the purpose of illustrating a practical embodiment thereof reference is had to the accom-

panying drawings, in which like reference characters designate the same parts in the several views, and in which—

Figure 1 is a perspective view showing a preferred embodiment of the invention; Fig. 2 is a horizontal sectional view on the line 2—2 of Fig. 3; Fig. 3 is a vertical transverse section on the line 3—3 of Fig. 2; Fig. 4 is a horizontal sectional view on a plane below the plane of Fig. 2 and indicated by the broken line 4—4 of Fig. 3; Fig. 5 is a front elevation of one of the coin magazines detached and a portion of which is shown broken away on the line 5—5 of Fig. 6; Fig. 6 is a vertical sectional detail on the line 6—6 of Fig. 5; and Fig. 7 is a vertical sectional detail on the line 7—7 of Fig. 2.

As shown by the drawings, the apparatus comprises a casing of substantial construction adapted to be supported upon a showcase, cashier's desk or the like, and having any suitable form or arrangement of doors, lids or drawers for gaining access to the interior thereof. To this end the casing is shown as having a top cover or lid 11 hinged at 12 along the upper rear edge of the casing and adapted to be locked shut in connection with a front vertical panel 13 by any suitable means indicated as a hasp 14. I also provide a door 15 of cylindrical curvature hinged at 16 to the lower edge of the panel 13 and adapted to be locked closed in connection with a horizontal plate or ledge 17.

Within the casing and preferably closely below the plate 17 is a base plate 18, the same extending rearwardly toward the back panel 19 and directly beneath the front portion of the top panel or lid 11. The base 18 constitutes the main support for the operating portions of the mechanism and may be secured in fixed rigid position by any suitable means as by being connected to the rigid vertical end and front panels 20 and 21 respectively. The door 15 is provided with a transparency 15' whereby the cashier may observe the condition of the magazines freely.

As above intimated, I provide a plurality of coin chambers or magazines 22 which, though of different caliber for manipulation of various denominations of coins, are otherwise all of the same character and will be so described. I show for convenience of illustration of a practical device, a series of

2
five of these magazines adapted for pennies, nickels, dimes, quarters and half dollars respectively. It, of course, will be understood that the number of these magazines may be 5 greater or less according to the requirements of any particular business.

At the front of each magazine is provided a vertical slot 23 whereby the number of coins therein may be seen, and on opposite 10 sides of such slot are preferably provided graduations 24 and 25, the former indicating the number of coins and the latter showing the monetary value of the same according to the denominations. The bottom of 15 each magazine is closed in any suitable manner as, for instance, by a plug 26 screwed into the lower end of the tubular structure, and having a stud 27 rectangular in cross section adapted to project downwardly into 20 and through a hole 28 in the base 18, whereby the magazine is held in fixed position and prevented from becoming inclined or rotated around its axis, although allowing it free to be lifted vertically out of the casing 25 when the lid is open for the purpose of emptying the magazine, refilling it, or making an inspection of the lower portion thereof.

The coins for each magazine are adapted 30 to fit substantially closely or loosely in the same in a pile one above another, the lowermost coin resting flatly upon the upper surface of the plug 26. The lower end of the magazine is formed with a horizontal slot 30 at its rear approximately of a semicircular form or equal to the internal diameter of the tube extending across the rear portion thereof on a level substantially flush with the upper surface of the plug. Likewise a 35 slot 31 is formed at the front of the magazine and in the same plane as the other slot which is understood to be the plane of the lowermost coin in the magazine. The slot 31, however, is of smaller area than the rear 40 slot and is adapted to receive the end or blade 32 of a plunger 33 projecting forwardly in a horizontal direction beyond the front of the casing and provided with a button or finger piece 34 bearing preferably a 45 slot indicating the denomination to which the plunger pertains. Each plunger is guided along the space between the ledge 17 and the base 18 by means of spacing blocks 50 secured, as shown in Fig. 2, to the upper 55 surface of the base 18 and also by means of the front panel 21 in which are formed a series of notches 36 in which the plungers 33 are guided. The extreme end of each of the blades 32 is adapted to lie normally outside 60 of the slot 31, but when the plunger is pushed, will enter freely into and through the slot 31 and engage squarely against the lowermost coin, causing it to be ejected rearwardly through the slot 30, the next upper coin being held from contact with the

portion of the magazine directly above the slot 30. When the plunger, however, is returned to its normal position, the position indicated in Fig. 3, by any suitable automatic means such as a spring 37, the bulk of 70 coins will drop. So long as there are any coins in the magazine, one of them will lie in the plane of the slots 30 and 31 ready to be ejected by a subsequent manipulation of the plunger. The spring 37 is connected 75 at one end at 38 to the casing and at its other end at 39 to a lug projecting downwardly from the plunger 33 through a slot 40 formed in the base 18.

Each coin ejected is adapted to drop into a chute 41 leading downwardly and outwardly in any suitable direction into a pocket or cup 42 shown in this instance as being secured at the front of the casing within reach of the cashier. Each chute 45 delivers through the casing wall in a slot 43 with which the chute registers. The receiving end of the chute is preferably widened out more on one side than on the other as indicated in Fig. 7, so as to make it impossible 90 for the coin to drop and bridge squarely across it. By this means the coin is caused to turn on edge or in a vertical plane in a position to roll down and freely out of the chute. 95

When a purchase is made requiring change, and assuming that the amount of change to be given the customer is thirty-five cents, the cashier will simply force the plungers marked 10 and 25 rearwardly so as to 100 eject a dime and a quarter, which coins will roll promptly into the pocket 42. If the amount of change required should necessitate the actuation of the same plunger a plurality of times, such actuation may be done 105 very rapidly and the coins will accordingly be ejected in rapid succession, all rolling down the same chute to the same point of delivery.

This device being adapted especially for 110 use where change must be made rapidly, and even though the cashier may at any time, by taking notice, observe the condition of the supply of the coins with respect to their magazines, yet it is desirable at times to prevent the actuation of the plungers when the magazines should happen to be empty. More definitely stated, should the pocket 42 be arranged at the rear or end of the casing, whereby the customer may receive directly 115 his own change therefrom, should any of the magazines be empty and hence fail to deliver, a controversy between the customer and the cashier might arise to the embarrassment of the latter. I therefore provide 120 an automatic locking device in connection with each magazine which prevents the operation of the plunger when such magazine is empty. Such locking device therefore 125 constitutes an indicator immediately ap- 130

prising the cashier that such magazine is empty, and the cashier will be governed accordingly. The automatic lock provided for this purpose comprises a dog 44 pivoted at 45 intermediate its ends transversely of the groove 29 formed in the plug 26. The front end of the dog is enlarged or bent upwardly forming a stop 44' and lying directly in the rear of the slot 31 when the magazine 10 is empty, the dog being swung on its pivot in such position by gravity acting downwardly upon the weighted rear end 46, as shown in Fig. 6. When, however, one or more coins are in the magazine, the dog will be held by 15 the lowermost coin so as not to obstruct the passage of the plunger blade as above described. The dog may be made strong enough for its purpose to prevent the movement of the plunger and yet may be sufficiently delicately pivoted to insure that a 20 single coin in the magazine will hold it down out of locking position, as shown in Fig. 3.

To insure that each plunger will be given a full stroke at each operation so as to cause the coin to be entirely ejected, I provide a pawl 47 pivoted freely upon the plunger and coöperating with a rack 48 fixed beneath the slot 40, the pawl 47 is slightly longer 30 than the vertical distance between its pivot and the rack and is adapted to swing free from the rack at each end of the stroke of the plunger. When the plunger is given its action stroke to eject the coin, the pawl 35 drags idly over the teeth of the rack, and when the stroke is completed it will drop beyond the rear end of the rack and hence will drag idly over the rack on the automatic return stroke of the plunger. If, however, 40 the stroke is too short to eject a coin, the pawl will not have left the rack, and being in an inclined position, will automatically lock the plunger from return under the force of the spring 37. Another impulse upon the 45 plunger, therefore, will be required to eject the needed coin.

The lid 11 may be fitted with any suitable size or form of funnel devices to guide the several denominations of coins into their respective magazines, such devices being indicated at 49. Under ordinary conditions, therefore, the cashier will place the coins received from the customers directly into the hoppers 49 where they will fall into proper 55 position in the several magazines. Should, however, any of the magazines become full or the cashier be too busy to assort the coins for this purpose, they may be laid temporarily on the ledge 17 or in any other convenient position. Currency and other matter 60 than coins may be placed in boxes or drawers indicated at 50 or in any other

unoccupied portion of the casing, held shut by a catch 51 and adapted to be projected when the catches are released by a spring 65 52. The catch may be released by a button 53 shown best in Fig. 4.

I claim:

1. In a change making machine, the combination of a casing, a substantially flat 70 horizontal base secured within the casing and provided with a series of rectangular sockets, a series of coin magazines having closed bottoms provided with rectangular lugs projecting freely downwardly into the 75 respective sockets, thereby holding the magazines from tilting or rotation, said magazine bottoms being provided with front and rear slots, and means acting through one of said slots to project a coin through the other 80 of said slots with respect to each magazine.

2. In a change making machine, the combination of a casing, a series of vertically arranged coin magazines supported in the casing and removable freely therefrom independently of one another through the top of the casing, each magazine having a solid closed bottom provided with a groove extending longitudinally therein from front to rear leaving coin supporting shoulders 90 on opposite sides of the groove, said magazine also having front and rear slots arranged in the same plane as the shoulders aforesaid, means normally arranged outside of the magazine but acting through the 95 front slot to eject a coin through the rear slot, and movable means mounted within the magazine in said groove and serving automatically when the magazine is empty to prevent the operation of the coin ejecting 100 means, said movable means being removable with the magazine.

3. In a device of the character set forth, the combination of a vertically disposed and vertically removable magazine of tubular 105 form and having at its lower end front and rear slots arranged in the same horizontal plane, a solid supporting plug secured in the lower end of the magazine and having its upper end lying in the same plane as said 110 slots, said plug being provided with a groove in its upper face extending below the plane of the slots and from one slot to the other, a dog pivoted intermediate its ends transversely of the groove, said dog having at its 115 front end a stop projecting upwardly and serving to close the front slot when the magazine is empty, said stop being held normally out of stop position by the lowermost coin when the magazine is occupied.

HYMAN ABRAMOVITZ.
